UNITED STATES PATENT OFFICE.

JOHN F. O'CONNOR, OF CHICAGO, ILLINOIS, ASSIGNOR, BY MESNE ASSIGNMENTS, TO
W. H. MINER, INC., A CORPORATION OF DELAWARE.

ANTIFRICTION BEARING.

Application filed December 22, 1922. Serial No. 608,391.

This invention relates to improvements in antifriction bearings.

One object of this invention is to provide an anti-friction bearing especially adapted for use as a side bearing on railway cars, and wherein the same may be attached to the body bolster of the car, and the anti-friction element proper made self-centering under the action of gravity and self-adjusting to compensate for variations in the angles between the body and the truck bolsters.

More specifically, the object of the invention is to provide a side bearing of the swinging pendulum type, wherein the anti-friction element is rotatably supported in a cradle having limited rocking movement longitudinally of the bolster.

In the drawings forming part of this specification, Figure 1 is a vertical sectional view taken through the ends of a body and a truck bolster of a railway car, showing my improvements in connection therewith. Fig. 2 is a sectional view corresponding substantially to the line 2-2 of Fig. 1, and Fig. 3 is a perspective view of the cradle or cross link used in connection with my improved anti-friction bearing.

In said drawings, 10 denotes the upper portion of a truck bolster of a railway car, 30 and 11 indicates the opposed lower part or section of a body bolster. The improved bearing comprises, broadly, a retaining member, housing or casing A, a cradle B, an anti-friction element C and a pair of supporting pivot members D and E.

The retaining member A, as shown, is of rectangular box-like construction, open at the top and bottom and provided with side walls 12 and end walls 13. The side walls 40 12 are downwardly tapered to provide downwardly and outwardly sloping inner faces 14, and at their upper ends are provided with integral ears 15 extending at right angles therefrom. The ears 15 serve as a 45 means for suspending the retaining member from the body bolster 11, being secured thereto in any suitable manner, preferably by rivets 16. Each of the end walls 13 is connected to the opposite side walls 14 by 50 a relatively thick web 121. The inner ends of the webs 121 are spaced apart a distance equal to the width of the cradle B, thus providing a recess 122 therebetween of proper

size to freely accommodate said cradle. The webs 121 are also provided with supporting 55 ribs 123 at their inner ends abutting the lower face of the body bolster 11.

The cradle B is of generally rectangular outline, as clearly shown in Fig. 3, and is provided with a downwardly extending, centrally located, cylindrical portion 17. The cylindrical portion 17 is perforated as indicated at 18 to receive the pivot pin D. The upper portion 19 of the cradle B is provided with a perforation 20 extending at right angles to the perforation 18 and is adapted to receive the pivot pin E.

The pivot pin E is arranged transversely of the body bolster 10, and extends through the perforation 20 of the cradle and alined 70 perforations 124 in the webs 121 of the retaining member. The opposite ends of the pin E are secured in countersunk recesses in the end walls 13, by being upset. The cradle B is thus directly supported on the 75 pin E for rocking movement within the recess 122. In this connection, it will be noted that the pivot pin E is supported for its entire length by the webs 121 and the cradle B, whereby bending of the pin during the application of the actuating pressure, is resisted. A slight clearance is left between the upper face 21 of said cradle and the lower face of the body bolster 10, and the upper face 21 of the cradle is cut away at 80 opposite sides of the center so as to provide outwardly extending downwardly sloping faces 22 to allow for proper clearance between the same and the body bolster, thereby permitting limited rocking movement of 85 the cradle within the retaining member A.

The anti-friction element C is of the swinging pendulum type, and is of general sector-like outline, being provided with a lower curved bearing face 23 adapted to coact with the upper face of the truck bolster 10, and inwardly and upwardly converging side faces 24 terminating in an upwardly extended portion 25. The portion 25 comprises spaced cylindrical members 26 adapted to loosely receive therebetween the portion 17 of the cradle B. The portions 26 have peripheral convex faces 27 slightly spaced from curved concave surfaces 28 of the cradle B to provide proper clearance for the free movement of element C. Between 90 100 105

- the members 26, the anti-friction element C is provided with a concave surface 29 slightly spaced from the convex surface 30 of the member 17 of the cradle B. The 5 portions 26 of the anti-friction element C are provided with perforations 31 concentric with the convex surfaces 27 and in alignment with the perforation 18 of the portion 17 of the cradle B, to receive the pivot pin 10 D. The anti-friction element C is thus 15 swingingly supported by the pivot pin D above its center of mass so that the same will be self-centering and under the action of gravity return to its normal position when the actuating pressure is removed.

- To resist wear of the pivot pins D and E, it is desirable to construct them of special material, and the same are preferably made of alloy steel and both heat-treated. 20 To reduce friction between the bearing surfaces of the pins D and E to a minimum and prevent cutting of said surfaces the cradle B and the anti-friction element C are preferably made of cast iron, whereby relatively soft bearing surfaces are provided on the cradle and anti-friction element which co-act with the smooth hardened surfaces of said pins D and E.

- In the operation of my improved anti-friction bearing, as the two bolsters 10 and 30 11 approach each other and shift radially, the bearing surface 23 of the anti-friction element C will roll on the upper surface of the truck bolster 10, the pressure being transmitted through the pin D to the cradle B and to the supporting pivot E of said cradle. During the operation of the anti-friction bearing, the pivotal connection between the retaining member A and the cradle B will 35 permit a limited rocking movement of the latter to compensate for variations in the angles between the body and the truck bolster. Upon removal of the actuating pressure from the bearing, the anti-friction element C, due to the force of gravity, will 40 swing to normal position by movement on the pivot pin D.

- I have herein shown and described what I now consider the preferred manner of carrying out the invention, but the same is merely illustrative, and I contemplate all changes and modifications that come within the scope of the claims appended hereto.

- I claim:
- 55 1. In an anti-friction bearing adapted to be secured to the under side of a bolster, the combination with a retaining member; of a carrier within said member, said member having webs at opposite sides spaced apart 60 a distance equal to the width of said carrier; a pivot pin extending through said carrier and webs, whereby said carrier is suspended; an anti-friction element; and a pin extending through said carrier and element above 65 the center of mass of the element at right

angles to said first-mentioned pin, whereby said element is adapted to return to its normal position under the influence of gravity.

2. In an anti-friction bearing adapted to be secured to the underside of a bolster, the combination with a retaining member; of a carrier within said member, said member having webs at the opposite sides spaced apart a distance equal to the width of said carrier; a single hardened pivot pin extending through said web and carrier above the center of mass of the latter, whereby said carrier may rock; an anti-friction element; and a single hardened pin extending through said carrier and element above the center of mass of the latter at right angles to said first-mentioned pin, whereby said element is adapted to return to its normal position under the influence of gravity.

3. In an anti-friction bearing adapted to be secured to the under-side of a body bolster, the combination with a retaining member secured to said bolster and having spaced downwardly projecting portions; of a carrier arranged transversely of the said retaining member, said carrier being mounted for pendulous movement in said retainer by means of a pin extending through the spaced downwardly projecting portions of said retaining member and through said carrier, said pin being placed in double shear, and adapted to take the load when imposed upon said carrier; an anti-friction rocker having spaced wall portions disposed at opposite sides of the portion of said carrier below said pin, the remainder of said rocker projecting below said spaced portions to provide a bearing member adapted to engage with an adjacent bolster; and a second pin for pivotally connecting said rocker to said carrier for pendulous movement at an angle to the movement of said carrier, said pin extending through the spaced wall portions of said rocker and the portion of said carrier below said first pin, whereby said second pin is placed in double shear.

4. In an anti-friction bearing adapted to be secured to the under side of a body bolster, the combination with a retaining member secured to said bolster and having downwardly extending end portions and downwardly extending side walls, the inner surfaces of said side walls diverging outwardly; of a carrier disposed in said retainer; a pivot pin extending through said carrier and the end portions of said retaining member to mount said carrier for rocking movement transversely of said retaining member, said carrier being adapted to bear against said pin under load, and being supported by said pin for pendulous movement in one direction; an anti-friction element; and a pivot pin extending through said element and said carrier below said first mentioned pivot pin and at an angle thereto, and arranged to sup-

port said anti-friction element in bearing relation with said carrier and permit pendulous movement of said element at an angle to said carrier, the diverging surfaces of the side walls of said retaining member permitting transverse swinging of said carrier and said anti-friction element, and said end

portions permitting pendulous movement of said anti-friction element.

In witness that I claim the foregoing I 10 have hereunto subscribed my name this 18th day of November, 1922.

JOHN F. O'CONNOR.
